UNITED STATES PATENT OFFICE.

HENRY WEBER, OF CHICAGO, ILLINOIS, ASSIGNOR TO LATHAM MACHINERY COMPANY, OF CHICAGO, ILLINOIS, A CORPORATION OF ILLINOIS.

UNIVERSAL WORK-SUPPORT FOR STITCHING-MACHINES.

1,382,036.

Specification of Letters Patent. Patented June 21, 1921.

Application filed June 20, 1919. Serial No. 305,645.

To all whom it may concern:

Be it known that I, HENRY WEBER, a citizen of the United States, residing at Chicago, in the county of Cook and State of Illinois, have invented certain new and useful Improvements in Universal Work-Supports for Stitching-Machines, of which the following is a specification.

My invention relates to work supports for wire stitching machines, and the like, and has for one of its objects the provision of a simple and efficient work-holding support which is adapted to be held rigidly in operative position and provided with means for quickly and easily swinging the device to a position for expeditiously placing work on and taking it off from such support.

A further object is the provision of a work table having a universal movement, that is, pivoted for swinging in a horizontal plane, when in operative position, and also for sliding back and forth on its support in such horizontal plane.

A still further object is the provision of a work support which will be held rigidly when in operative position and provided with means for first unlocking the device, then for swinging the device out of operative position by a simple continuous movement of an operating device.

Other objects will appear hereinafter.

An embodiment of my invention is indicated in the accompanying drawings, forming a part of this specification, and in which—

Figure 1 is a fragmental elevation of a device embodying my invention;

Figs. 2 and 3 are enlarged sections taken on lines 2—2 and 3—3, respectively, of Fig. 1;

Fig. 4 is an enlarged detail section showing the bottom portion of the work support;

Fig. 5 is an enlarged fragmental side view of the upper portion of my work support showing a box in section thereon; and

Fig. 6 is a similar view of a work support now in use with a box in section on it.

Referring more particularly to the drawings, I have indicated in Fig. 1 a base 5 and upright 6 of a wire stitching machine in

order to show the application of my improvement to such machines. The stitching head is not shown.

On the base 5 is indicated a frame 7 secured thereto by screws 8, or the like. The frame 7 may be a casting or formed in any desirable manner of a suitable material. The frame 7 preferably comprises two sides 9 and a back 10. This is simply a convenient form and any other desirable arrangement may be used. Extending through the sides 9 is a pin 11 which serves as the pivot pin for the work support. On the pin 11, between the sides 9 is an upright arm 12 having a horizontal portion 13 extending laterally from the pin 11 forming a substantially L-shaped member. The upright part 12 may be made in any desirable manner. I have shown it as being a casting extending upwardly from the pin 11 with a tubular sleeve attached on the upper portion of the casting. A stop 14 is preferably mounted on the wall 10 adapted to engage a corresponding stop 15 on the part 12 to limit the movement of the member 12 toward the stop 14. The stop 14 may be a screw threaded in the part 10, as indicated, or any other desirable form of stop may be used. A tension spring 16, or its equivalent, is secured between the members 12 and 6 to hold the member 12 in its upright position and against the stop 14. This simply indicates one form of resilient means for maintaining the upright arm 12 in the position indicated.

The horizontal part 13 has a portion 13' adapted to rest on top of a bolt 17 which is slidably mounted on the base 5 or in any other desirable manner so that the part 13' resting on the bolt 17 holds the arm 12—13 against swinging away from the stop 14. The bolt 17 is provided with a compression spring 18, or its equivalent, which normally holds it in position to engage the part 13'. The part 13' may be a hardened plate secured to the part 13 by rivets 19, or in any other desirable manner.

Also pivoted on the pin 11 is a lever 20. This lever 20 in the present instance is mounted for convenient operation by the operator's foot and may be a pedal. The lever 20 is provided with a downwardly ex-

tending finger 21 which normally rests against an end of bolt 17. The finger resting against the bolt 17 limits the movement of the bolt in one direction. The arrangement is such that when pressure is applied to the lever 20, the finger 21 will move the bolt 17 inwardly toward spring 18 until the bolt disengages the part 13', when the arm 12-13 will not be locked against moving away from stop 14. The space 22 between the lower side of lever 20 and upper side of part 13 is such that by the time the finger 21 has moved the bolt 17 from under part 13', the under side of lever 20 will engage the top of part 13 and the continued downward movement of the lever 20 will swing the arm 12-13 away from stop 14, thereby moving the upper end of the arm 12 out of its operating position to a position where work may be changed on the table at the top of said part 12. Upon releasing the lever 20, the spring 16 automatically moves the part 12 back to the position shown in Figs. 1 and 4, and the spring 18 moves the lever 20 to its position shown in Fig. 4.

The top of member 12 is preferably hollow, as indicated, and at any rate is constructed in such manner so that a member 23 may be mounted for adjustment longitudinally of the member 12. In the form shown I have indicated the member 23 as being slidably mounted inside of the tubular part of member 12. On the member 23 I have indicated a knurled nut 24 threaded so that by moving the nut 24 along on the member 23, the latter is adjusted longitudinally of the part 12 of the arm. A screw 25 may be threaded in the arm 12 with its inner end extending into a slot 26 to prevent rotary movement of the member 23 in the arm 12 when there is a tendency of the member 23 to move in said member 12.

At the upper end of the member 23 I provide a cylindrical part 27 upon which is pivoted a head 28. The head 28 is provided at its upper end with parallel portions 29 which engage a trackway 30 of a work table 31. The table 31 may be locked on the head 28 in any desirable manner, such as by the plates 32 being secured by screws 33, or their equivalent. This arrangement is such that the head 28 and table 31 are free to rotate on the part 27, and the table 31 is free to slide laterally of the member 27 on the head 28. This gives a kind of universal movement to the work table so that work placed upon the table is supported substantially horizontally while in position to be operated on by the stitching mechanism, not shown, and free to be moved about to support the work to stitch any desired part thereof. The member 27 is preferably provided with an opening 34 for holding the anvil part of the stitching mechanism, not shown. The table 31 is therefore provided

with an opening 35 so that this riveting anvil is accessible through the table 31.

In Fig. 5 I have indicated a box 36 on the work table 31 ready to be operated upon by the stitching mechanism. From this figure 70 it will be apparent that the box may be slid laterally of the part 12 from one limit to the other of the sliding movement of table 31 so that with the rotary movement of the table on part 27 all parts of the side of the 75 box being stitched are accessible to the stitching mechanism and are always held in position so that the rivets pass straight through the parts of the box stitched.

In Fig. 6 I have indicated an ordinary 80 work support now on the market on which a box 36 is indicated. The only surface engaging the box is the riveting anvil 37, and since this member is comparatively small it is quite difficult to hold a box so that 85 its side being stitched is level or in a position for the stitching wire to pass straight through the box side. From comparing Figs. 5 and 6 it will be apparent that with my work table mounted in the manner indicated the box can be easily and accurately held in position for proper stitching, while in Fig. 6 if the box is not held with its side being stitched horizontal, the stitching wire passes through the box at an angle and has 95 a tendency to buckle or draw the parts being stitched, making an imperfect construction.

I claim:—

1. A work support for stitching machines comprising an upright arm pivoted at its 100 lower end; a locking member engaging a portion of the arm and hold the latter against movement in one direction; and a lever having a part adapted to engage said locking member in the first part of its movement for disengaging said locking member from said part of the arm and in the rest of its movement being adapted to move the arm on its pivot.

2. A work support for stitching machines 110 comprising an upright arm pivoted at its lower end; a locking member extending under and holding the arm against swinging in one direction; a lever having a portion adapted to move the locking member from 115 under said arm and another portion for engaging the arm to swing the latter on its pivot; and a work table at the upper end of said arm.

3. A work support for stitching machines 120 comprising a frame; a pivot pin mounted in the frame; a member pivoted on said pin and having a part disposed substantially vertically and another part disposed substantially horizontally; a work supporting 125 table at the top of said vertical part; a locking bolt extending under said horizontal part; a lever having a portion adapted to engage and remove said bolt from under said horizontal part and a portion adapted to 130

engage said horizontal part of the member and swing the latter on its pivot.

4. A work support for stitching machines comprising a frame; a pin mounted in the frame; a substantially L-shaped arm pivoted on said pin with one part disposed horizontally and the other part disposed vertically; a work supporting table at the top of the vertical part; a locking bolt slidably mounted and extending under said horizontal part holding the arm from rocking in one direction; a stop on the frame engaging said vertical part and holding the arm against movement in the other direction; and a lever pivoted on said pin and having a part adapted to engage the bolt and move the latter out of engagement with said horizontal part and a part adapted to engage the horizontal part of said arm and rock said vertical part away from said stop.

5. A work support for stitching machines comprising a substantially L-shaped arm pivotally mounted at its angular portion and having one part extending horizontally and another part extending vertically; a lock engaging said horizontal part and holding the arm against pivotal movement in one direction; a lever spaced normally from said horizontal part and adapted for movement against said horizontal part for swinging the latter on its pivot; and a finger on said lever adapted to move the lock out of engagement with said horizontal part before the latter is engaged by said lever.

35 6. A work support for stitching machines comprising a substantially L-shaped arm pivoted at its angular portion and having one part extending vertically and the other part extending horizontally; a locking bolt extending under said horizontal part; a stop engaging said vertical part, said stop and said locking bolt holding the L-shaped arm against swinging; a lever spaced normally above said horizontal part; and a finger on said lever engaging said locking bolt, the downward movement of said lever being adapted to cause said finger to move the locking bolt from under said horizontal part and the lever to engage said horizontal part and swing said vertical part away from said stop.

7. A work support for stitching machines comprising an upright arm mounted for lateral swinging; a head pivoted at the upper end of said arm for unobstructed swinging in a plane at right angles to said arm; and a work table freely slideable laterally on said head.

8. A work support for stitching machines

comprising an upright arm pivoted at its lower end; a member mounted in the top of said arm and adapted for adjustment longitudinally of said arm; a head pivoted on said member; and a work table slidably mounted on said head, said head and work table being adapted for free swinging and sliding movements respectively by an operator of the stitching machine.

9. A work support for stitching machines comprising an upright arm pivoted at its lower end and having its upper end hollow; a member disposed in and extending upwardly from said hollow end; a nut threaded on said member and engaging the upper end of said arm and adapted to adjust said member longitudinally of said arm; a head pivoted for free swinging on said member and having portions with parallel edges at its upper end; and a work table having a trackway engaging the parallel edges of said head.

10. A work support for stitching machines comprising an upright arm pivoted at its lower end and having its upper end hollow; a member extending into said hollow end; a spline connection between said member and said hollow end; a nut threaded on said member and engaging the upper end of said arm for adjusting said member longitudinally of the arm; a head pivoted on the upper end of said member for free manual swinging; a work table having a trackway therein; and portions on said member having parallel edges engaging said trackway providing a free and unobstructed sliding connection between the work table and said member.

11. A work support for stitching machines comprising an upright arm pivoted at its lower end and having a portion extending laterally; a lock engaging the laterally extending part of said arm holding the latter against swinging in one direction; means for disengaging said lock from said laterally extending portion of the arm and moving the arm on its pivot; a head pivoted on the upper end of said arm; and a work table having its upper surface disposed in a plane substantially at right angles to the axis of said head, there being a sliding connection between the table and head permitting the table to slide laterally of the axis of said head and always in a plane substantially at right angles to said axis.

In testimony whereof I have signed my name to this specification on this 17th day of June, A. D. 1919.

HENRY WEBER.
